UNITED STATES PATENT OFFICE.

JAMES J. WOOD, OF FORT WAYNE, INDIANA, ASSIGNOR TO GENERAL ELECTRIC COMPANY, A CORPORATION OF NEW YORK.

TUB FOR WASHING MACHINES.

Application filed August 10, 1920. Serial No. 402,644.

To all whom it may concern:

Be it known that I, JAMES J. Wood, a citizen of the United States, residing at Fort Wayne, county of Allen, State of Indiana, 5 have invented certain new and useful Improvements in Tubs for Washing Machines, of which the following is a specification.

The present invention relates to tubs for washing machines and specifically to that 10 type which is moved bodily back and forth in a vertical plane and at the same time is given a rocking motion about a horizontal axis for the purpose of causing the water employed for washing to surge back and forth, said water having a path of movement approximating a figure 8, the axis of which is horizontal.

Owing to the fact that a considerable weight of water has to be employed which 20 is augmented by the weight of the clothes being washed, the problem of properly supporting a relatively thin sheet metal tub is not so simple as it would first appear. Furthermore, the tub must be maintained water 25 tight and the securing means must be of such character as not to injure the clothes or stain them with rust, etc.

The object of my invention is to provide an improved arrangement for supporting 30 washing machine tubs of the character described, which is strong and simple in construction and one which will not injure the fabrics being washed.

For a consideration of what I believe to 35 be novel and my invention, attention is directed to the accompanying description and the claims appended thereto.

In the drawing, Fig. 1 is a side elevation of a tub; Fig. 2 is an end view of the same, 40 and Fig. 3 is an enlarged detail view of one of the combined supports and securing devices.

5 indicates a cast metal frame or end plate usually of iron, whose periphery corresponds more or less closely to that of the 45 tub. Two of these frames are provided, one on each side of the tub, and are generally similar. 6 indicates a frame member which has an opening 7 at its upper end to receive 50 a horizontal pivot, the latter being supported by an oscillating arm, not shown. Branching outwardly from the upper end of the member are two braces 8 and 9. The

lower end of the member 6 is formed integral with the lower part of the main 55 frame and extends below the same to receive a centralizing spring, not shown. 10 indicates a boss containing an opening 11 to receive a pin carried by the upper end of a connecting rod, not shown, whereby the tub 60 may be rocked or oscillated on its horizontal axis.

The tub 12 is made of relatively thin metal and its sides conform in general to the outline of the frame. The bottom of the 65 tub has transversely extending flutes 13 which assist in the washing operation. The top, bottom and ends of the tub may be formed of one or more sheets of metal arranged to fill in the space between the sides. 70 The joints between the sides and said sheet or sheets should be so made as to be watertight. Preferably the tub is made of relatively thin sheet copper and coated with tin on the inside to prevent corrosion or injury 75 to the fabrics being washed. A suitable removable cover is provided for the tub through which water and clothing to be washed are introduced. A suitable drain plug for the water will also be employed. 80

To securely fasten the tub to the side frames and to prevent buckling of the sides it is necessary to provide a comparatively large number of fastenings. One of these is shown in enlarged section in Fig. 3. Before 85 the side walls of the tub are united with the bottom, ends and top a series of holes are punched therein at the desired places. Instead of making simple holes the portion of the metal around each hole is forced outwardly to form a conical projection 15 which when the parts are assembled fit into conical recesses in the side frames. These projections assist in holding the tub in the frame because any tendency of the tub to 90 move in a direction parallel with the side members of the frame is resisted by them. In other words these projections would have to be sheared off before any appreciable movement could take place. The projections also form seats for the screws 16 which 100 seats being of copper are slightly yielding, and they also present a comparatively large amount of metal to the head of the screw without making the head of the latter unduly large. The fact that each projection

15 extends well into a smooth conical seat in the frame means that the packing surface is large as compared to the diameter of the screw and owing to the tapered head on the 5 screw the metal of the tub is tightly wedged between said head and the seat, thereby forming a water tight seal. Furthermore, since the heads of the screws are countersunk, that is to say, are flush with the wall 10 as distinguished from projecting into the tub, they cannot injure the fabric being washed.

Opposite each screw the frame is provided with a small enlargement 17, the purpose of which is to provide sufficient metal 15 to receive the threads of the screws without the same projecting through the frame and also to avoid the necessity of making the frame heavier than is otherwise necessary.

20 After the tub is mounted in the frame and secured in place by the screws, the heads of the latter are covered with solder 18 which not only makes certain that there will be no leakage around the screw heads 25 but prevents the same from working loose. The solder should be applied in such manner that the exposed surface is perfectly smooth. It will be observed that the peripheral portion of the tub is secured to the 30 frame members by a plurality of fastenings and also that the sides of the tub are secured to the braces and in this manner the tub as a whole is securely held in place and the sides are also held against buckling.

35 In accordance with the provisions of the patent statutes, I have described the principle of operation of my invention, together with the apparatus which I now consider to represent the best embodiment thereof, 40 but I desire to have it understood that the apparatus shown is only illustrative and that the invention may be carried out by other means.

What I claim as new and desire to secure by Letters Patent of the United States, is: 45

1. A washing machine tub comprising a pair of side frames, each having a plurality of recesses, a sheet metal tub having hollow projections which enter said recesses, and means for securing the tub to the frames 50 which extend through said projections into the side frames.

2. A washing machine tub comprising a pair of side frames, each having a plurality of conical recesses, a sheet metal tub having 55 hollow projections which enter said recesses, and means which extend through the projections into the side frames and hold the walls of said projections in fluid-tight contact with the walls of the recesses. 60

3. A washing machine tub comprising a pair of spaced frame members, the opposed surfaces of which have recesses, a sheet metal tub which is located between the frame members, said tub having outwardly extending 65 hollow projections which fit into said recesses, and screws which extend outwardly from the tub and through the projections into the frame members, the heads of the screws holding the walls of the projections 70 in fluid-tight contact with the walls of the recesses.

4. A washing machine tub comprising a pair of side frames, each having a plurality of conical recesses, a sheet metal tub having 75 hollow conical projections which enter the recesses, screws which extend through the projections into the side frames, and hold the walls of said projections in fluid-tight contact with the walls of the recesses, and means covering the heads of the screws which prevent them from backing out and also prevent fluid from having access thereto. 80

In witness whereof, I have hereunto set my hand this 6th day of August, 1920.

JAMES J. WOOD.
